UNITED STATES PATENT OFFICE.

ALEX HARRIS, OF CHICOOPEE FALLS, MASSACHUSETTS, ASSIGNOR TO DRAPER CORPORATION, OF HOPEDALE, MASSACHUSETTS, A CORPORATION OF MAINE.

ROCKER-SHAFT BEARING FOR LOOMS.

Application filed June 17, 1925. Serial No. 37,853.

This invention relates to the lay rocker shaft bearings, of which there are two, one located in each side frame of the loom. These bearings support the weight of the lay swords, the lay, the shuttle boxes and any other mechanism carried by the lay. As the lay is oscillated at each pick during the weaving operation, this continual movement, with its continual reversal of direction, causes considerable wear between the rocker shaft and its bearings, which, if not compensated for, results in lost motion and the downward displacement of the lay and the parts supported thereby, thus affecting the cooperation of the lay and the parts carried thereby with the remainder of the loom and interfering with the proper weaving operation.

The main object of the present invention is to provide a simple and effective construction of rocker shaft bearing which shall be readily adjustable to compensate for this deleterious wear as it occurs without altering the position of the lay rocker shaft itself. It is quite important that the lay rocker shaft, which is carefully adjusted into required and definite position with respect to the loom frame when the loom is assembled, shall remain in such position. The present invention, while permitting adjustment to compensate for wear, leaves undisturbed this assembly adjustment and insures that the position of the lay rocker shaft shall not be altered.

The nature and objects of the invention will appear more fully from the accompanying description and drawings and will be particularly pointed out in the claims.

As the construction with which the present invention is concerned is the same at both sides of the loom, except for the reversal of the parts, it will be sufficient to illustrate and describe a preferred form of construction at one side of the loom only, and, furthermore, as the invention relates solely to the rocker shaft bearing, it is only necessary to illustrate and describe those parts of the loom immediately concerned therewith.

In the drawings:

Fig. 1 is a view of a front portion of a loom partially in vertical cross section looking from the interior toward the left-hand side frame with a preferred form of the present invention embodied therein.

Fig. 2 is a view in side elevation looking toward the outside or the opposite side of the lower portion of the loom frame shown in Fig. 1.

Fig. 3 is a top plan view of the lower bearing member.

Fig. 4 is a view of the complete bearing with the loom frame shown in horizontal cross section.

Fig. 5 is a view in cross section taken on the line 5—5 of Fig. 4.

Fig. 6 is a view in vertical cross section taken on the line 6—6 of Fig. 2.

The side frames of the loom, the left-hand one 1 of which is illustrated, are connected transversely at the front by the breast beam 2 and the lay rocker shaft 3. Each side frame is usually provided with horizontal, outwardly extending flanges or feet 4 resting upon the floor. The lay rocker shaft 3 supports, and has mounted thereon inside the side frames, the lay swords 5, usually formed at the bottom with hub portions 6 secured to the shaft by set screws 7. The lay swords at their upper ends support the transversely extending lay 8 with the race plate 9 upon which the shuttle travels, the shuttle boxes at each end which are not shown, the hand rail 10 with the reed and the other usual parts. The lay rocker shaft 3 with its supported load is constantly oscillated during the weaving operation by a connection 11, usually from the crank shaft of the loom. It will thus be seen, as already pointed out, that the weight of the lay swords, the lay and the supported parts, together with the shock and jar of this constant oscillatory movement, produce wear particularly between the lower surface of the lay rocker shaft and that portion of the bearing surface cooperating therewith which, unless compensated for, results in a lowering of the rocker shaft and all the parts supported by it.

The bearing construction provided by this invention is shown in detail in a preferred form as arranged for the left-hand side of the loom. It comprises essentially two main parts, namely, an upper bearing member and a lower bearing member. The former is designed to present an extended upper bearing surface for the lay rocker shaft which shall, after the usual assembly adjustment, remain in fixed position, thus assuring the proper position of the rocker

shaft and its supported parts, while the latter is designed also to present an extended lower bearing surface to be readily adjustable to compensate for wear without disturbing the required positions of the rocker shaft and the upper bearing member.

5 The side frame of the loom is provided with a transverse aperture 12 to permit the passage therethrough of the bearing portions of the bearing members with the lay rocker shaft and of sufficient size to allow for a reasonable adjustment or positioning in any direction so that, particularly in assembling the parts, the lay rocker shaft 10 may be accurately located. Both bearing members are clamped together face to face and are located on the outer face of the side frame where they are readily accessible.

15 The upper bearing member comprises a generally flat plate 13 extending well to each side of the aperture 12 and, when in position, resting against the outer face of the loom frame. This plate has formed integral therewith a downwardly facing segmental hub 14 of considerable length and adapted to extend well through the aperture 12 and afford an extended bearing for the shaft 3. The plate 13 is provided near each end with apertures 15 which embrace 20 bolts 16 mounted in the side frame. The plate 13 may thus be adjusted on the bolts to position the bearing portion 14 and consequently the rocker shaft 3. Usually after the proper position has been effected, the 25 plate 13 is secured in place by pins 17 passed therethrough and through the side frame. The lower bearing member also comprises a substantially flat plate 18 extending alongside the plate 13, but at its center dropping 30 below the position of the shaft 3. This plate at one end is pivotally mounted upon one of the bolts 16 and is usually provided with a stop 19 adapted to swing against a shoulder 20 on the plate 13 to limit the 35 downward swinging movement of the plate 18. At the other end, the plate 18 is slotted vertically to slide over the bolt 16 as the plate 18 is swung about its pivotal axis. This plate is provided at the same free end 40 with a prolongation 22 in which is threaded a set screw 23 having a lock nut 24. This set screw seats on the flange foot 4 of the side frame and presents a means for vertically adjusting the free end of the plate 18 45 with respect to the side frame and consequently with respect to the plate 13 secured thereto. The lower bearing member also 50 comprises integral with the plate 18 an upwardly facing segmental hub 25 extending 55 from the plate through the aperture of the frame 12 and presenting an extended lower bearing surface for the rocker shaft 3.

60 As will be seen, particularly from Fig. 5, the downwardly facing segmental hub 14 has a substantially semi-circular bearing 65

surface, and below this bearing surface the side walls of the hub 26 are formed concentrically with the pivotal axis of the bolt 16 upon which the plate 18 pivots. These side walls 26 continue through the plate 13 and thus form an opening through the plate beneath the bearing area of the hub. The upwardly facing segmental hub 25 projects through this opening in the plate 13 and fits in between the walls 26, and its side 70 walls 27 are substantially concentric with this pivotal axis. Hence, as the lower bearing member is adjusted about its pivotal axis by means of the adjusting device 23, or otherwise, the upwardly facing segmental hub 25 is adjusted toward or from the downwardly facing segmental hub 14.

75 It will thus be seen that the downwardly facing segmental hub 14, which constitutes the upper bearing surface for the lay rocker 80 shaft, after assembling, always remains in fixed position and as this bearing surface is subject to a very little wear, the position of the lay rocker shaft, if held up against it, remains unchanged. It will also be seen 85 that the lower bearing member provides a simple and efficient means by which any wear taking place at the lower bearing surface of the rocker shaft is readily compensated for by adjusting this lower bearing member upwardly. This may be done very accurately by means of the set screw 23 and the lower bearing member after adjustment is held very rigidly and firmly in 90 place by tightening up the nuts 28 on the bolts 16. When these nuts are tightened up, the two bearing members are firmly secured together and are also firmly secured 95 to the loom side frame.

100 The extended segmental hubs present both below and above the rocker shaft long extended bearings throughout their entire length. The lower bearing member on its outer face is also provided with a recess or depression 29 to provide clearance for the usual hub on the bearing shoe member, not shown, which is mounted on the lay rocker shaft to support the picker shoe.

105 There is thus presented a simple, practical and efficient lay rocker shaft bearing which may be readily applied to existing looms, as well as embodied in looms when first constructed. The principle of adjustment of the lower bearing member by pivoting at one end on the upper bearing member and provided with a device for vertically adjusting the free end is also applicable 110 to other than the segmental hub structure.

115 Having thus described my invention, what is claimed as new, and desired to be secured by Letters Patent, is:

120 1. In a lay rocker shaft bearing for looms, the combination of a side frame of the loom having a transverse aperture and a foot flange; an upper bearing member compris- 125

ing a plate resting against the outer face of the frame and a downwardly facing segmental hub projecting therefrom through the aperture in the frame, the said plate having an opening therethrough beneath the bearing area of the said hub; and a lower bearing member comprising a plate resting against the outer face of the first plate, pivoted at one end on the said first plate and provided at the other end with an adjusting device seated on the frame foot flange, and an upwardly facing segmental hub projecting therefrom through the first plate opening and through the frame aperture and presenting a bearing surface beneath and complementary to that of the first segmental hub, whereby an extended bearing is presented to both the top and bottom surfaces of the rocker shaft with the upper bearing surface throughout always in fixed position while the entire lower bearing surface, where wear occurs, is readily and accurately adjustable to compensate for such wear without disturbing the required position of the rocker shaft.

2. In a lay rocker shaft bearing for looms, the combination of a side frame of the loom having a transverse aperture; an upper bearing member comprising a plate resting against the outer face of the frame and a downwardly facing segmental hub projecting therefrom through the aperture in the frame, the said plate having an opening therethrough beneath the bearing area of the said hub; and a lower bearing member comprising a plate resting against the outer face of the first plate and pivoted at one end on the said first plate, means for vertically adjusting the free end of the second plate with respect to the first plate, and an upwardly facing segmental hub projecting therefrom through the first plate opening and through the frame aperture and presenting a bearing surface beneath and complementary to that of the first segmental hub, whereby an extended bearing is presented to both the top and bottom surfaces of the rocker shaft with the upper bearing surface throughout always in fixed position while the entire lower bearing surface, where wear occurs, is readily and accurately adjustable to compensate for such wear without disturbing the required position of the rocker shaft.

3. A lay rocker shaft bearing for looms having the construction defined in claim 2, in which the walls of the opening in the first plate and the walls of the lower segmental hub projecting from the second plate through said opening are concentric with the pivotal axis of the second plate.

4. A lay rocker shaft bearing for looms having the construction defined in claim 2, in which both plates are firmly secured to-

gether and to the side frame in properly adjusted position by bolts, one coaxial with said pivotal axis and one at the opposite ends of the plates, and in which the second plate is vertically slotted to fit the latter bolt and provide for the required adjustment.

5. In a lay rocker shaft bearing for looms, the combination of a side frame of the loom having a transverse aperture and a foot flange; a bearing member comprising a plate resting against the outer face of the frame and a bearing portion projecting therefrom through the aperture in the frame; and a second bearing member comprising a plate resting against the outer face of the first plate, pivoted at one end on the said first plate, and provided at the other end with an adjusting device seated on the frame foot flange, the said plate having a bearing portion facing upwardly to present a bearing surface beneath the rocker shaft, whereby, by adjusting the second plate about its pivotal axis on the first plate, wear of the shaft and bearing may be compensated for without disturbing the required position of the rocker shaft.

6. A lay rocker shaft bearing for looms having the construction defined in claim 5, in which both plates are firmly secured together and to the side frame in properly adjusted position by bolts, one coaxial with said pivotal axis and one at the opposite ends of the plates, and in which the second plate is vertically slotted to fit the latter bolt and provide for the required adjustment.

7. In a lay rocker shaft bearing for looms, the combination of a side frame of a loom having a transverse aperture; a bearing member comprising a plate resting against the outer face of the frame and a bearing portion projecting therefrom through the aperture in the frame; a pair of bolts located one at each end of the plate passing through the plate and frame and securing them together; and a second bearing member comprising a plate resting against the outer face of the first plate, pivoted at one end on one of said bolts, provided at the other end with a vertical slot fitting over the other bolt and with means for vertically adjusting the free end with respect to the first plate, the said second plate having a bearing portion facing upwardly to present a bearing surface beneath the rocker shaft whereby, by adjusting the second plate about its pivotal axis, wear of the shaft and bearing may be compensated for without disturbing the required position of the rocker shaft.

In testimony whereof, I have signed my name to this specification.

ALEX HARRIS.
